UNITED STATES PATENT OFFICE.

THIEBEAUD GALLAT, OF CINCINNATI, OHIO.

CATCH-BASIN.

SPECIFICATION forming part of Letters Patent No. 279,374, dated June 12, 1883.

Application filed March 19, 1883. (No model.)

To all whom it may concern:

Be it known that I, THIEBEAUD GALLAT, of Cincinnati, Hamilton county, Ohio, have invented a new and useful Improvement in 5 Catch-Basins, of which the following is a specification.

The object of my invention is to provide a means for reducing to small fragments the more intractable matters which clog catch-basins and cess-pools in order to enable their 10 more ready removal.

In the accompanying drawings, Figure 1 is a perspective view of a portion of a catch-basin embodying my improvement. Fig. 2 is a 15 half ground plan and half vertical section of the same.

A may represent a part of the floor, and B portions of the walls of a catch-basin.

C may represent a customary ventage or 20 outlet in the floor of the basin.

D represents a valve, which in its lowest position closes the outlet C.

E are stanchions grouped in a circle, and serving to retain in place a turn-table, F, 25 which is upheld by legs G, that are armed with cleavers H, which, when the table F is partially rotated, act shearwise with similar cleavers, J, that project from the stanchions E. Other legs, I, of the table, on diametrically 30 remote sides thereof, have vertical grooves for shanks K of a bar, L, which is fastened to the valve D. These shanks carry a plate, M, which is armed with teeth m, which partial rotation of the table F brings in antagonism

35 with stationary teeth e, that project inward from the stanchions E, for the purpose of reducing coarse matters to small fragments.

The legs G I are secured at their lower extremities to a false bottom, N, wheels O in

which facilitate its rotation upon the basin- 40 floor.

Depressions n in false bottom N facilitate the collection in front of the cleavers of such clogging objects as bottles, rocks, and the like. The shanks K, being extended upward through 45 the turn-table, as shown, are connected to levers P, whose heels, being depressed by arms Q, that project from shaft R, as shown in Fig. 1, operate to lift the valve D. This action is brought about by a slight rotation of the shaft 50 R. A further rotation of shaft R brings its arms Q against the studs S upon the turn-table F, and causes its greater or less rotation with the effects above noted.

Staples T on the turn-table serve to hold 55 down the ends of the arms Q upon shaft R. Rollers q q' on the arms Q facilitate their working.

I claim as new and of my invention—

1. The combination, with a sewer catch-basin, of stanchions E, armed with cleavers J and the turn-table F, armed with cleavers H, as and for the purpose set forth.

2. The combination, with a sewer catch-basin, of stanchions E, armed with teeth e, 65 and the turn-table F, armed with teeth m, as and for the purpose set forth.

3. In a catch-basin, the combination of valve D, shanks K, toothed plates M, levers P, and the shaft R, having arms Q, as and for the 70 purpose set forth.

In testimony of which invention I hereunto set my hand.

THIEBEAUD GALLAT.
